UNITED STATES PATENT OFFICE.

CHARLES D. MOSHER, OF HYDE PARK, MASSACHUSETTS.

PLATE AIR HEATER.

Application filed December 31, 1927. Serial No. 243,895.

REISSUED

This invention relates to air-heating structures utilizing waste heat from a boiler furnace or other source, to heat air for a useful purpose.

8 The structure in which the invention is embodied is of the plate type, and comprises an air-conducting casing adapted to receive hot gases at one end and discharge the same at the opposite end, and having large side 10 openings at its upper and lower end portions, a group of air chambers extending side by side lengthwise of the casing, each chamber having relatively wide side plates, united at their edges to form a thin air passage, ob- 15 long in cross section, the chambers being provided at their end portions with ports regis- tering with the casing openings, the arrange- ment being such that the casing is adapted to conduct hot gases upwardly between the 20 chambers, while the chambers downwardly conduct air admitted to their upper ends through ports at the upper front ends of the chambers, heated air being discharged through ports at the lower forward or rear 25 ends of the chambers.

The chief object of the invention is to provide an air-heating structure, the air chambers of which are adapted to be conveniently installed, with either end at the top, and re- 30 versed end to end after a period of use, so that when the upper end portions of the chambers are impaired by corrosion, due to the use of sulphurous fuel, this corrosion occurring chiefly at the cooler upper end por- 35 tions, the chambers may be reversed to locate uncorroded portions thereof uppermost, and thus practically double the life of the cham- bers.

Another object is to provide improved 40 means associated with the ports of the chambers for filling the casing openings, to prevent leakage of gases from the casing around the ports.

Another object is to provide an improved 45 construction of the chambers at the ports thereof, whereby tapering throats are formed to facilitate the flow of air into the ports at the upper end portions of the chambers.

Other related objects will hereinafter ap- 50 pear.

Of the accompanying drawings forming a part of this specification,—

Figure 1 is a front elevation of an air heater embodying the invention.

Figure 2 is a longitudinal section on line 55 2—2 of Figure 1.

Figure 3 is an enlargement of a portion of Figure 2.

Figure 4 is a fragmentary section on line 4—4 of Figure 1.

Figure 5 is a fragmentary section on line 5—5 of Figure 1.

Figure 6 is a perspective view, showing one of the clips hereinafter described.

Figure 7 is a perspective view of one of the 65 air chambers.

Figure 8 is a section on line 8—8 of Fig- ure 7.

Figure 9 is a section on line 9—9 of Fig- ure 7.

Figure 10 is an enlarged fragmentary sec- tion on line 10—10 of Figure 1.

Figure 11 is a fragmentary section, show- ing two of the chambers.

Figure 12 shows in perspective portions of 75 one of the chambers, and a portion of a filling member intended to be engaged with the chambers, as shown by Figure 7.

The same reference characters indicate the same parts in all of the figures.

12 designates a vertically elongated heat- 80 conducting casing, adapted to receive hot gases at its lower end, and discharge the same at its upper end. A large rectangular upper opening 13 is formed in the upper end por- 85 tion of the casing, and a lower opening 14, of the same size and form, is formed in the lower end portion of the casing, the opening 13 ad- mitting cool air to the upper ends of the chambers hereinafter described, and the 90 lower opening permitting the discharge of hot air from the lower ends of said cham- bers.

Within the casing is a group of air cham- 95 bers extending side by side lengthwise of the casing. Each chamber includes a pair of parallel rectangular plates 15, united at their edges, preferably by welding, to form a thin air passage, which is oblong in cross section. One longitudinal edge of the chamber has 100 at its upper end portion an air inlet port at 16, registering with the upper casing opening 13, and an air outlet port 17, at its lower end portion registering with the lower casing opening 14.

The chambers are provided with filling members 18, a portion of one of which is shown separately by Figures 11 and 12. Said

members surround the ports and are formed to collectively close the casing openings around the chambers, and space the chambers apart, as shown by Figure 10, the joints of said members being made up with plastic cement unaffected by heat.

I provide means adapted to detachably secure the chambers to the casing, so that they may be detached, reversed end for end, and again attached, the form of the chambers and the form and arrangement of the attaching means being such that the chambers are reversible. I prefer to embody the attaching means in tie bolts 19, connected with and projecting from the forward edges of the chambers, above and below the ports thereof, said bolts being adapted to enter holes formed for their reception in the casing, and provided with clamping nuts 20 (Figure 3). In this instance, the bolts 19 are engaged directly with the filling members 18, as best shown by Figures 3 and 11. Said filling members are, in this instance, provided with slots 21, receiving ears or wings 22, formed on the outer edges of the chambers and forming the opposite sides of the air ports. Said wings are of the angular form shown by Figures 8, 10 and 11, and constitute diverging sides of throats 24 (Figure 11), which facilitate the entrance of cool air into the upper ports of the chambers, and prevent the formation of air eddies outside the ports.

To extend the throats 24, I provide angular clips 25, formed as shown by Figures 6 and 10, of sheet or plate metal, adapted to be sprung upon the angular ears 22, and connect the ears on adjacent air chambers.

The filling members 18 are abutted together, as shown by Figures 10 and 11, and are separable from each other. Said members form a series filling the casing openings around the ports of the air chambers. One end member of the series contacts with a fixed abutment 26 (Figure 4) on the casing. The opposite end member contacts with a movable clamping abutment 27 (Figures 5 and 10), which is adjustable to clamp the filling members together and confine the air chambers suitably spaced apart.

The casing is provided with means for adjusting the abutment 27, preferably embodied in a slide 28, on which the abutment 27 is formed, said slide being movable on a guide 29, fixed to the casing and provided with an ear 30, receiving a rod 31. The head 32 of the rod bears on the inner side of a portion of the casing 12, and a nut 33 engaged with a threaded portion of the rod bears on the ear 30. When the nut is turned in one direction, it moves the slide 28 to press the abutment 27 inwardly, and cause its clamping action. The slide is guided by a fixed bolt 34, passing through a slot 35 in the slide.

The abutting edges of its filling members

18 are preferably provided with interengaged shoulders 36, formed to maintain the members in alinement with each other, as shown by Figures 10 and 11.

To prevent inward buckling of the plates 15, forming the sides of the air chambers, I secure to one plate of each chamber, longitudinally extending angle strips 37, bearing on the opposite plate.

One plate of each series may be provided with external angle strips or lugs 38, adapted to bear on an adjacent chamber and maintain the predetermined spacing between the chambers. One wall of the casing may be provided with a spacing strip 39, having notches 40 (Figure 10) adapted to engage the vertical inner edges of the air chambers, said edges being preferably V-shaped.

I claim:

1. An air heater of the plate type, comprising a heat-conducting casing adapted to receive hot gases at one end and discharge the same at the opposite end, and having side openings at its end portions, a group of air chambers extending side by side lengthwise of the casing, each chamber including a pair of parallel rectangular plates united at their edges to form a thin air passage which is oblong in cross section, one longitudinal edge of the chamber having at one end portion an air inlet port registering with one of the casing openings, and at its opposite end portion an air outlet port registering with the other casing opening, and attaching means adapted to detachably secure the chambers to the casing, the form of the chambers and the attaching means permitting the reversal of the chambers end for end, the chambers being provided with filling members surrounding the ports and formed to collectively close the casing openings around the chambers and space the chambers apart, the arrangement being such that the casing is adapted to conduct hot gases in one direction between the chambers, while the chambers conduct air in the opposite direction from the inlet to the outlet port.

2. An air heater as specified by claim 1, the chamber attaching means being embodied in tie bolts engaged with and projecting from the edges of the chambers above and below the ports, and adapted to enter registering bolt holes in the casing and provided with clamping nuts.

3. An air heater as specified by claim 1, the filling members being separately abutted together edge to edge and forming a series filling the casing openings, one end member of the series contacting with a fixed abutment on the casing, the heater comprising also a movable clamping abutment bearing on the opposite end of the series, and means for adjusting said abutment to clamp the filling members together and confine the chambers in spaced apart relation.

4. An air heater as specified by claim 1, the abutting edges of the filling members being shouldered and interengaged to maintain the members in alinement.
5. An air heater as specified by claim 1, the chambers being provided with diverging angular wings projecting therefrom at opposite sides of the ports and forming the sides of tapering throats communicating with the chambers, the wings of adjacent chambers being connected by angular clips sprung upon the angular wings and forming extensions of said throats.

In testimony whereof I have affixed my signature.

CHARLES D. MOSHER.
